Primary Examiner — Steven J Czyz*(74) Attorney, Agent, or Firm* — Seth M. Reiss, AAL, ALLLC(57) **CLAIM**

I claim the ornamental design for a roll-on umbrella stand, substantially as shown and described.

DESCRIPTION

FIG. 1 is a top perspective view of the stand portion of the roll-on umbrella stand shown separately for ease of disclosure;

FIG. 2 is a bottom perspective view of a roll-on umbrella stand;

FIG. 3 is a top plan view of the stand portion of the roll-on umbrella stand shown separately for ease of disclosure;

FIG. 4 is a bottom plan view of the roll-on umbrella stand; FIG. 5 is a left side view of the stand portion of the roll-on umbrella stand shown separately for ease of disclosure;

FIG. 6 is a right side view of the roll-on umbrella stand shown in use with environment;

FIG. 7 is a front view of the stand portion of the roll-on umbrella stand shown separately for ease of disclosure;

FIG. 8 is a back view of the roll-on umbrella stand shown in use with environment; and,

FIG. 9 is a top perspective view of the table surface portion of the roll-on umbrella stand shown separately for ease of disclosure.

The broken lines depict environment that form no part of the claimed design.

1 Claim, 7 Drawing Sheets(56)
